UNITED STATES PATENT OFFICE.

WILLIAM K. BISHOP, OF BINGHAMTON, NEW YORK, ASSIGNOR TO THE BREWER-TITCHENER CORPORATION, OF CORTLAND, NEW YORK, A CORPORATION OF NEW YORK.

LIGHT FOR VEHICLE CURTAINS.

Application filed September 15, 1924. Serial No. 737,692.

To all whom it may concern:

Be it known that I, WILLIAM K. BISHOP, a citizen of the United States, and a resident of Binghamton, and the county of Broome 5 and the State of New York, have invented certain new and useful Improvements in Lights for Vehicle Curtains, of which the following is a specification.

My invention relates to a window frame 10 and more particularly pertains to a window or light adapted to be formed through an opening in the curtain of an automobile or other vehicle.

The object of this invention is to provide 15 for simple and economical installation of the sheet metal frame structure which mounts the window pane in the curtain fabric and at the same time to provide effective means for ready replacement in the 20 event the pane becomes broken or should otherwise need renewal. In certain respects, this latter feature represents an improvement upon my co-pending applications Serial No. 668,530 filed October 15, 1923, 25 and Serial No. 730,842 filed August 8, 1924.

A two-part sheet metal frame is preferably used for present purposes comprising a finishing or outer member and a complementary back or inner member. Simple 30 and novel means are provided for binding the marginal edges of the fabric opening between these frame parts in such fashion that the structure as a whole may be interlocked without resorting to separate fastening devices or prongs of any kind.

This end may be accomplished by the use 35 of an endless outer frame member having a bowed or dished cross-sectional shape equipped with an internal flat flange that circum- 40 scribes and bears against the marginal portion of one face of the transparent pane. The dished inner frame is further provided with a set of spaced overhung lugs that project inwardly from the respective longitudinal edges of said dished contour and constitute an undercut annular slot therebetween.

The separate complementary back or inner frame is provided with a modified type 50 of internally disposed flat flange adapted to bear upon the opposite face of the pane, the profile of this internal flange being preferably such as to impart the desired amount of resiliency thereto and allow the pane to

be gripped between the set of internal 55 flanges in a sprung relation. Formed integrally with and around the internal flange of the backing frame, is an off-set grooved male part preferably of a cross-sectionally rectangular profile, which part is initially 60 shaped to be received within the registering annular slot or female part of the outer frame member. The curtain fabric is then firmly clamped between the nested male and female parts and securely gripped thereby, 65 while the marginal portion of the pane is held between and loosely centered by the surrounding internal flanges of the respective frame members.

When the two frame members are assembled about the pane, the walls defining the groove in the rearward side of the male part of the backing member will be exposed to view. This prerequisite is taken advantage of in fastening the frame parts together by 70 means of a novel crimp or indented cleat formed integral with the side walls of said rectangular male offset. A cleat is formed by either crimping, indenting, or expanding 75 the relatively thin sheet metal side wall of 80 said male part outwardly so as to grip in under the respective adjacent overhung lugs of the nested female part. A plurality of such cleats are suitably spaced and serve to interlock the inner frame part with the 85 outer frame part after these members have been properly assembled in place with the curtain fabric interwoven therebetween.

Provision also has been made for readily 90 removing the pane from the assembled frame and curtain fabric. This is brought about by opening an end portion of one of said internal flanges of a four-sided style of frame and providing for a removable keeper 95 piece to span this gap and complete the enclosure about the pane. The abutting ends of the keeper are preferably made to telescope into socket portions formed in the end faces of said flange gap and novel means are provided for snap fastening the keeper 100 in place behind the pane. When the keeper is removed, the pane may easily be shoved endwise out from between the respective internal flanges of the frame members and through said frame gap without interfering 105 with the cleated tie of the curtain fabric.

Embodied herein are also certain improved features of structure and organiza-

tion designed to facilitate the manufacture and application of said curtain frame, all of which will be set forth in detail hereinafter.

Reference is had to the accompanying one sheet drawing which illustrates an example of the preferred form of my invention; like characters of reference indicate like parts in the several views, and in which drawings:

Fig. 1, is an elevational front view of the outer frame member and the pane mounted in a curtain fabric showing the detachable keeper piece removed.

Fig. 2, is a side view of Fig. 1 as seen from the keeper end.

Fig. 3, is a cross-sectional view of the assembled frame and curtain fabric as taken along the line 3—3 of Fig. 1 but showing the keeper piece in place.

Fig. 4, is a plan view of the keeper piece while Fig. 5 is a cross-section of same as taken along line 5—5 of Fig. 4.

Fig. 6, is an enlarged sectional view of the similar right hand detail shown in Fig. 3 and Fig. 7 represents an enlarged view of the similar left hand detail shown in Fig. 3.

In these drawings, the letter "A" represents the sheet metal outer frame member in its entirety and "B" is the transparent pane mounted therein. The frame A is provided with an internal flange A₁ adapted to bear against the marginal portion of one side of the pane. Formed integral with said flange A₁ is a cross-sectionally dished or bowed offset A₂, the outermost longitudinal edge of which terminates in a foot flange A₃. Said flange is further provided with an inturned annular lug A₄ that overhangs and follows the outer longitudinal edge of the dished offset A₂.

The opposite or innermost longitudinal edge of the endless dished offset A₂ is likewise provided with a complementary in-turned annular lug A₅, which is shown as an extension of the internal flange A₁, and spaced from the lug A₄ to form the slot or female part therebetween, designated as A₆. This endless slot is disposed about the pane and preferably follows the frame contour. The elements A₄ and A₅ substantially lie in a common plane with the face of the internal flange A₁ and this plane defines the parting face of the two part frame members.

Referring more specifically to some further constructive details of the preferred style of the outer frame A, it will be observed from Figs. 6 and 7 that this frame is formed up from a single blank of sheet metal and that the internal flange A₁ is preferably reinforced by bending the inner marginal brim edge of the pierced sheet metal back upon itself to constitute the described inner overhung lug A₅. The foot flange A₃ is formed in a similar manner to constitute the inturned endless overhung lug A₄.

In assembling the frame, the interposed

fabric C is intended to initially lie along said aligned parting face. The pane B is then mounted against the internal flange A₁ of the outer frame and preferably cushioned by the interposed fabric C as shown in Fig. 7. The opposite side of the marginal edge of the pane B is gripped by a especially shaped internal flange D₁ formed integral with the inner or backing frame and this second member of my two part frame is designated as a whole by the letter "D".

A bead-like element D₁' is provided for said flange D₁ for the purpose of augmenting the resiliency of the latter with respect to the opposite internal flange A₁ as well as to the intermediate pane B. In the present instance, the flange D₁, and its bead D₁' are not made endless as are the remaining rectangular frame parts but that said elements are cut away along one of the short ends so as to terminate in the respective sockets D₁₁ and D₁₂ and form a gap therebetween.

The outermost longitudinal edge of said bead-like element D₁' is sharply bent up into a plane substantially parallel to the internal flange D₁, that is to say, the face of the pane B but disposed in an offset relation thereto, so as to constitute the relatively narrow intermediate flange D₁₀ and this flange is preferably made endless so as to connect the frame across the open gap formed between the sockets D₁₁ and D₁₂.

The outermost edge of said continuous intermediate flange D₁₀ is then sharply bent into an endless annular side wall D₂ which is disposed substantially normal to the plane of the pane B and loosely encircles and serves to partially center same. The transverse wall D₂ is made of sufficient length to project considerably beyond the thickness of the pane B, whereupon the sheet metal of the backing frame is again bent outwardly and away from the internal flange D₁ to form the bottom wall D₃. The face dimension of this bottom wall is determined by the width A₆ of the receiving slot in the female member as will appear hereinafter. The sheet metal is further bent back to form another annular side wall D₄ which is substantially parallel with the side wall D₂. The inner frame member is finally flared outward and away from the wall D₄ to form the circumscribing flange D₅.

The transverse side walls D₂ and D₄ together with the integral bottom wall D₃ enclose an endless annular groove of substantially uniform width formed in the inner frame D which groove, designated as D₆, constitutes the male part of this frame and is preferably disposed around the contour of the pane B. The exterior faces of the spaced walls D₂ and D₄ register with and are intended to initially enter freely into the undercut slot D₆ of the outer frame member A.

It will be observed that said male member is kept spaced from the bead-like element D_1' by means of the connecting intermediate flange D_{10} , which is preferably made to align 5 with the plane of the circumscribing flange D_5 . Said flange D_{10} is adapted to bear against the inner overhung lug A_5 and it thus serves as one of the stop faces for the entrance of the male part into the female 10 part when the assembled two-part frame is interlocked by means of my indented crimp cleats in the manner presently to be described.

For assembling the parts of my frame 15 they are brought into the relation indicated in Fig. 3 and it will be seen that the curtain fabric C is intended to lie between the inner and outer frame flanges. The members A and D are snugly sprung together causing 20 the margin of the opening in the fabric C to take a circuitous path about the nested male and female frame parts as is more clearly shown in Fig. 7.

While in this strained or sprung relation, 25 the male and female flange parts are interlocked in a novel manner by means of a crimping tool adapted to be inserted into the open side of the exposed groove D_6 , all of which has been more fully disclosed in my 30 copending applications previously referred to. An oblong tool is preferably used for this purpose, and this is provided with a head portion having a length somewhat longer than the width D_6 of said groove, so 35 that a partial turning of the head will serve either to expand the indented cleats in the side walls D_2 and D_4 or if preferred, serves to cut indentures through said walls and form up ear-like projecting spurs such as 40 are designated as D_7 and D_8 in Fig. 6. These spurs thereby become interlocked with the respective overhung lugs A_4 and A_5 of the female part and firmly bind the edges of the 45 fabric opening into the assembled frame to make a permanent leak-proof joint therewith. The described indenture causes the crimp cleats D_7 and D_8 to project outwardly 50 from their respective side walls in such fashion that their overall width is now greater than the slot width A_6 and becomes 55 positively interlocked therewith.

It is pointed out that an important feature 55 of my present improvements lies in the facilities provided for removing the pane from a two-part frame assembled, especially when cleated to an interwoven curtain fabric in the manner described. It will be seen from Fig. 1 that one end portion of the backing frame is left open to constitute the described 60 gap and that the pane B is intended to be held in place by the detachable keeper E such as is shown in Figs. 4 and 5. This keeper is of a shape adapted to fit across and span the gap made by the described cut out in 65 the elements D_1 and D_1' and is preferably

made to fill in the normal contour of the inner frame. To this end, the U-shaped keeper is provided with a bead element E_{10} , also a flange portion E_5 adapted to lie flat on the exposed parting face of the outer frame A. 70 The end portions of the keeper bead E_{10} are provided with relatively short projections E_1 and E_2 intended to telescope into the respective sockets D_{11} and D_{12} of the inner frame D, which thus secure the abutting 75 squared ends of the keeper into the cut out or gap of the member D. A novel method for locking this keeper in place is provided for, and for this purpose a relatively short clip D_9 is preferably raised out of the face 80 of the circumscribing flange D_5 in the manner best indicated in Fig. 6. This clip is sloped inwardly toward the pane and after the projections E_1 and E_2 have been properly entered into their sockets, the outermost 85 edge of the flange E_5 may be snapped down in place behind the beveled clip D_9 .

When it is desired to remove the pane, the keeper E can readily be sprung out of place 90 by disengaging the outer edge of the keeper flange E_5 from the clip D_9 , whereupon the projections E_1 and E_2 may be withdrawn from their respective sockets D_{11} and D_{12} . Thus, while the curtain is still interlocked 95 with the two-part frame members, the pane 100 B may now be slipped laterally out of the sash groove formed between the set of opened complementary internal flanges D_1 and A_1 in the manner indicated by dotted and dashed lines in Figs. 1 and 3. During 105 this operation the raised clip D_9 is slightly depressed by springing away the frame and allowing the pane to pass over same. The slight inherent resiliency imparted to the internal flange D_1 by the bead D_1' , serves to 110 facilitate the removal of the pane and provides for a limited give to meet variations in the thickness of the renewed pane. In order to further facilitate the insertion of a new pane, the fabric C may be cemented or otherwise secured to its adjacent flange A_1 so as to hold the fabric against this flat face and prevent wrinkling. After a replacement pane has been reinserted into the frame, the keeper may be snapped back in place in the 115 manner shown in Figs. 3 and 6.

It will be seen that the pane replacement operation is simple and may easily be performed even by such user of my curtain light frame who may not be especially skilled in the automobile trimmer's art, and that this may be accomplished without in anyway disturbing the novel cleated tie that interlocks the nested frame members with marginal edges in the fabric opening. 120

While the preferred embodiment of my removable keeper has been set forth in detail as used in combination with the described indented cleat means for permanently fastening the two part frames together, it 125 130

will be understood that my novel devices are subject to a rather wide latitude in their application; as an instance, it will be apparent that instead of utilizing snap clip D_9 , substantially equivalent result as to holding the keeper in place may be had by the use of screws, dowels and the like fastening means. If desired, the gap provided for the renewal of the pane may be cut back further so as to 10 include the intermediate flange A_{10} , but it is pointed out that the sheet metal actually used for this flange is kept relatively thin. Hence when the frame members are sprung apart, this thin metal ridge A_{10} will not prevent the 15 removal of the pane as might be inferred from abnormal metal thickness shown in Fig. 6.

Furthermore, it is not essential that the slot A_6 as formed between the outer frame 20 lugs A_4 and A_5 , be made endless since a series of spaced shorter slots or female parts suitably encompassing the contour of the pane B will serve the same purpose. In that event, the nested male parts would be correspondingly shortened so as to again register 25 with such modified slots. It will also be understood that the male frame parts need not necessarily be shaped in the rectangular fashion shown in the drawings, and that various 30 changes in the details of my keeper device may be resorted to without departing from the spirit and scope of my invention, heretofore described and more particularly set forth in the appended claims.

35 Claims:

1. In a curtain light frame comprising members adapted to be nested, a male part for one of the members and a registering female part for the other member, an internal flange for each of said frame members of which one flange is provided with a gap, a bead-like element for said gapped flange serving to impart augmented resiliency thereto, a pane mounted between said 40 flanges and removable through said gap, a detachable keeper adapted to span said gap and retain the assembled pane in place, and indented cleat means between the male and female parts serving to interlock and 45 snugly hold said flanges against the pane.

2. In a curtain light frame comprising members adapted to be nested, a male part for one of the members and a registering female part for the other member, an internal flange for each of said frame members of which one flange is provided with a gap, a pane mounted between said flanges and removable therefrom through said gap, means serving to detachably retain the assembled pane in place, and indented cleat 55 means interlocking said flanges about the pane.

3. In a curtain light frame comprising members adapted to be nested, a male part 60 for one of the members and a registering

female part for the other member, an internal flange for each of said members of which one flange is provided with a gap, a pane mounted between said flanges and removable therefrom through said gap, a curtain fabric 70 mounted between the pane and one of said flanges, and indented cleat means between the male and female parts interlocking said flanges about the pane.

4. In a curtain light comprising complementary endless frame members, a set of internally disposed lugs for one of said members, a male part for the other member adapted to nest between said lugs, said male part being disposed transversely with respect to said lugs and extending across the parting surface between said frame members, a curtain fabric interposed between the male part and said lugs, an indented cleat means serving to positively interlock 80 said fabric with the frame members, an internal flange for each of said members of which one flange is provided with a gap, a pane having its marginal faces mounted between said flanges and removable therefrom through said gap, a detachable keeper means adapted to span said gap, and means for securing the keeper in place behind the edge of said pane.

5. In a curtain light comprising complementary endless frame members, a set of internally disposed lugs for one of said members, a male part for the other member adapted to nest between said lugs, said male part being disposed transversely with respect to said lugs and extending across the parting surface between said frame members, curtain fabric interposed between the male part and said lugs, an indented cleat means serving to positively interlock 90 said fabric with the frame members, an internal flange for each of said members of which one flange is provided with bead-like element and a gap therefor equipt with a set of spaced sockets, a pane having its marginal faces mounted between said internal flanges and removable therefrom through said gap, a detachable keeper device adapted to span said gap, said keeper being provided with a set of projections adapted to 100 engage the respective sockets, and means for replaceably retaining the keeper in place behind the edge of the pane.

6. In a curtain light comprising a pane and complementary frame members therefor, a set of oppositely disposed lugs for one of said members constituting a female part, a male part for the other member adapted to nest within the female part, said male part being disposed transversely with respect to the face of the pane and extending across the parting surface between said frame members, indented cleat means for interlocking 110 said male and female parts, an internally disposed flange for one of said frame mem- 115 bers, 120

bers adapted to bear against the marginal portion of one face of the pane, a gap for said internal flange through which said pane is slidably removable, means carried by the other frame member adapted to engage the opposite face of the pane, a keeper means, and means for detachably securing the keeper to the frame and replaceably hold the pane in place.

10. 7. A curtain light frame comprising members for holding a pane, one of which members is provided with a female part and the other with a male part initially shaped to be received within the female part, the male part being expanded or indented within the female part aforesaid when the members are assembled around the pane, and means including a detachable keeper device for replaceably mounting the pane in said interlocked frame members.

8. In a sheet metal curtain light frame comprising complementary members for holding a removably mounted pane, an internal flange for each of said frame members of which frame one flange is provided with a gap, a pane having its marginal faces slidably mounted between said flanges and removable therefrom through said gap, a curtain fabric interposed between said frame members and permanently interlocked therewith, and a detachable keeper means serving to close said gap and replaceably retain said pane in the frame.

9. In a set of complementary endless frame members for holding a pane, one of which members is provided with a female part adapted to encompass the contour of

the pane, and the other member of which is provided with a registering male part initially shaped to be received within said female part, the male part being expanded or indented within the female part aforesaid when the members are assembled around the pane, an internal flange and a circumscribing flange for the member which is equipped with said male part, an intermediate flange disposed between said male part and the internal flange, said intermediate flange together with said circumscribing flange serving as a stop for the entrance of the male part into the female part.

10. In a set of complementary frame members for holding a pane, one of which members is provided with a female part adapted to encompass the contour of the pane, and the other member of which is provided with the registering male part initially shaped to be received within said female part, an internal flange for one of said members adapted to bear against the marginal portion of one face of the pane, means including a bead-like element serving to impart augmented resiliency to said internal flange, means carried by the other frame member adapted to engage the opposite face of the pane, and indented cleat means between the male and female parts for interlocking said frame members about the pane.

In testimony whereof, I have herewith set my hand this 12th day of September, 1924.

WILLIAM K. BISHOP.
